CLAIM

The ornamental design for a protective case for mobile computing device, as shown and described.

DESCRIPTION

FIG. 1 is an exploded top perspective view of the protective case for mobile computing device showing my new design with the parts of the case separated for clarity of disclosure; FIG. 2 is an exploded bottom perspective view thereof; FIG. 3 is a top perspective view thereof showing the protective case in an assembled state;

FIG. 4 is a bottom perspective view thereof;

FIG. 5 is a side view thereof;

FIG. 6 is a top plan view thereof;

FIG. 7 is a side view thereof;

FIG. 8 is a bottom plan view of the protective case in an unsecured state with an environmental mobile computing device;

FIG. 9 is a bottom plan view of the protective case in a secured state with an environmental mobile computing device; and, FIG. 10 is a bottom plan view of the protective case in a secured state with an environmental mobile computing device and with the central trigger arm in an alternate position.

The broken lines in FIGS. 8–10 depict an environmental mobile computing device that forms no part of the claimed design.
